LADY'S SHOE HEEL

Eleanor A. Mehr, Harvey, Ill.

Application May 25, 1959, Serial No. 56,059

Term of patent 14 years

(Cl. D7—5)

Figure 6 is a side view of the heel assembled to a shoe. The dotted line showing is to present the appearance of the heel when applied to a shoe.

I claim:

The ornamental design for a lady's shoe heel, as shown and described.
